United States Patent Office

Des. 228,338
Patented Sept. 11, 1973

228,338

BATH MAT

Robert A. O'Neil and Michael C. Wilson, Wheaton, Ill.,
assignors to Pretty Products, Inc., Coshocton, Ohio

Filed Feb. 14, 1972, Ser. No. 226,390

Term of patent 14 years

Int. Cl. D6—11

U.S. Cl. D7—210

FIG. 1 is a top plan view of a bath mat embodying our design.

FIG. 2 is a front side elevational view of the bath mat of FIG. 1.

FIG. 3 is a fragmentary vertical sectional view on an enlarged scale taken along line 3-3 of FIG. 1.

FIG. 4 is a fragmentary vertical sectional view on an enlarged scale taken along line 4-4 of FIG. 1.

We claim:

The ornamental design for a bath mat, as shown.
